M. S. Orton,
ATTORNEYS

UNITED STATES PATENT OFFICE.

GEORGE C. MOXON, OF NEW YORK, N. Y.

PAPER-FASTENING CLASP.

1,335,850.

Specification of Letters Patent.

Patented Apr. 6, 1920.

Application filed September 25, 1917. Serial No. 193,059.

To all whom it may concern:

Be it known that I, GEORGE C. MOXON, a citizen of the United States, and resident of New York city, in the county of New York and State of New York, have invented new and useful Improvements in Paper-Fastening Clasps, of which the following is a specification.

My invention relates in general to a fastening clasp and particularly relates to such a device designed for use in connection with clasp envelopes and similar stationery. This application is directed to an improvement over the device disclosed in my co-pending 15 application for envelop clasps, filed December 22, 1914, Serial No. 878,485 and allowed May 23rd, 1917.

In the device disclosed in my above identified application it was found that when the 20 clasps were mounted on envelopes and the envelopes stacked, the pressure of the envelopes would press on the bill portion of the clasp forcing the bendable finger at the end thereof into fastened engagement with its 25 holding means. It was therefore necessary for the user, first to separate the bendable finger from its holding means before the clasp could be used. Obviously this was not only annoying but where a frail grade 30 of metal was used the bending back of the finger tended to break it off.

Accordingly, one of the objects of my present invention is to provide a construction of clamp designed to protect the bendable finger against any accidental closing into its fastened position.

A further object of the invention is to provide an improved form of bendable finger guiding means designed to be stamped 40 from the body portion of the clasp and free of edges which may tear the envelop or associated parts.

Still another object of the invention is to provide an improved means for fastening 45 the clasp to the envelop associated therewith in such a manner that the configuration of the clasp will be maintained through the reinforcing effect of the portion of the envelop engaged by the base of the clasp.

A still further object of the invention is to reinforce the bendable member without the necessity of adding material to give the necessary reinforcement where thin metal 50 is used to form the clasp.

Various other objects and advantages of the invention will be in part obvious from

an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:

Figure 1 is a perspective view showing an open envelop with a preferred embodiment of my invention in position thereon;

Fig. 2 is a view in rear elevation of the device shown in Fig. 1;

Fig. 3 is a view similar to Fig. 2 showing the bendable finger in locked position;

Fig. 4 is a transverse sectional view taken on the line 4—4 of Fig. 2 and

Fig. 5 is a transverse sectional view taken 75 through the clasp applied to the envelop and in its fastened position.

While the invention is obviously of general application wherever a plurality of penetratable members are to be fastened together it will be described in its application 80 with reference to envelopes of the type used in mailing catalogues and the like.

In the drawings there is illustrated an envelop having a back portion 10 and a flap 11, designed to overlap the outer portion of said back to close the opening of the envelop as is usual with devices of this character. The clasp is preferably a one-piece sheet metal member die stamped to 90 form and having a base portion 12, opposite ends of which are fastened to the back 10 by means of punch eyelets 14. The clasp also includes a strip 15 bent forwardly from one end of the base portion to overlap the 95 same and to form a bill portion positioned above and extending parallel to the base portion. The free end of the bill portion opposite the bend 16 is bent inwardly at a sharp angle toward the base portion to 100 form a bendable finger 17. The bill portion is preferably reduced in width from the bend 16 toward the finger 17 to effect a saving of material. The finger terminates in a sharp edge 18 adapted to punch its way 105 through the flap 11 in a manner hereinafter described. The portion of the base adjacent the bendable finger 17 is pressed out of the plane of the base portion to form a V-shaped projection 19 designed to extend beyond the 110 bill portion as shown in Fig. 5, when the bendable finger 17 is moved toward the

base portion. The side of the projection facing the bendable finger is constructed to provide a means for engaging the finger and to bend the same back under the belt portion and into a locked position. This means is formed of two parallel slots 20, Z-shape in plane oppositely disposed and co-acting to form a pair of shoulders 21. The portion of the projection 22, which is positioned between the slots, is pressed back out of the plane of the balance of the projection so as to position the shoulders 21 forwardly of the projection as shown more particularly in Fig. 4. The space between the shoulders 21 is of a width greater than the width of the finger adjacent its free end but is of less width than the portion of the finger which underlaps the shoulders when the finger is in its fully underlapped position.

20 In order to reinforce the bill portion and at the same time provide a smooth thumb engaging surface, the central part of the bill portion is pressed forwardly to form an embossment 23. This flat embossment 23 tends not only to reinforce the bill portion against distortional strains but prevents the operator's finger from engaging the edges of the bill which may be left sharp by the pressing and die-cutting operation.

30 In operation, the flap of the envelop is lapped over the open end and positioned between the bill and base portions of the clasp. It is not necessary that the flap be perforated, but the flap may be provided with a 35 perforation or a series of perforations to contain the finger if desired. Pressure is exerted on the bill portion to force the same into position parallel and relatively close to the base portion or into engagement with the 40 back of the flap. This action forces the finger through whatever portion of the flap happens to be in line with the same and onto the incline provided by the portion 22. Continuing the pressure at the free end of the 45 bill causes the finger to be bent by the incline until it fits within the slot and hooks under the shoulders 21 as shown in Fig. 5 in which position it is held by the rigidity of the metal.

50 When the clasp is positioned on envelops and packed for shipping, it is obvious that the envelops will crowd the bill portion inwardly toward the base portion but this crowding action of the envelops cannot force 55 the finger back of the shoulders. The projection 19 which extends outwardly from the base a distance sufficient to overlap the bill portion receives the thrust of any article 60 pressing on the bill portion before the bendable finger is moved into its fully clasped position engaging the shoulders 21. In this way accidental locking of the envelop is prevented and accidental moving of the bendable finger into its finally locked position, is 65 avoided.

The parts are made of the lightest possible metal and the necessary strength is incorporated in the construction first by the strengthening of the bill portion through the embossing of the same and the base portion is strengthened both by the offset projection and by the disposition of the eyelets on opposite sides of the bent portion of the base. Where the eyelets engage stiff cardboard and the like, the base portion can be 75 made relatively light and dependence made upon the cardboard for the necessary rigidity.

While I have shown and described, and have pointed out in the annexed claims, certain novel features of my invention, it will be understood that various omissions, substitutions and changes in the form and details of the device illustrated and in its operation may be made by those skilled in the art 85 without departing from the spirit of the invention.

Having thus described my invention, I claim:—

1. A clasp for fastening the flap to the body portion of an envelop comprising a one-piece metal member having a base portion, means for fastening the base portion to the envelop, said base portion provided with a bill portion positioned above and extending parallel to the base portion, the free end of said bill portion being defined by a bendable finger projecting toward the base portion, said base portion provided with means for bending the finger when the latter is purposely pressed into engagement with said bending means, and means associated with said bendable finger for preventing an accidental engagement of the bendable finger with said bending means.

2. A clasp for fastening the flap to the body portion of an envelop comprising a one-piece metal member having a base portion and means for fastening the base portion to the envelop, said base portion provided with a bill portion positioned above and extending parallel to the base portion, the free end of said bill portion being defined by a bendable finger projecting toward the base portion, said base portion provided with means for bending the finger when the latter is purposely pressed into engagement with said bending means, said base portion provided with a projection on the side thereof facing the bill portion and positioned to the outside of the bill portion when the latter is pressed toward the base portion.

3. A clasp for fastening the flap to the body portion of an envelop comprising a one-piece metal member having a base portion, means for fastening the base portion to the envelop, said base portion provided with a bill portion positioned above and extending parallel to the base portion, the free end of said bill portion being defined by a bend-

able finger projecting toward the base portion, said base portion provided with means for bending the finger when the latter is purposely pressed into engagement with 5 said bending means, said base portion provided with a projection on the side thereof facing the bill portion and positioned to the outside of the bill portion when the latter is pressed toward the base portion, the bending 10 means being so positioned relative to the top of the projection that the bill must be pressed below the top of the projection to engage said bending means.

4. A clasp for fastening the flap to the 15 body portion of an envelop comprising a one piece metal member having a flat base portion, eyelets adjacent opposite ends of the base portion for fastening the same to the envelop said base portion being bent intermediate 20 the eyelets to form a projection extending to one side of the plane of the base portion, a bill portion positioned on the same side as the projection and having its free end reduced in width to form a bendable 25 finger adapted to be moved with the bill portion toward the base portion and to one side of the projection and means carried by the base portion for engaging said bendable finger.

30 5. A clasp for fastening the flap to the body portion of an envelop comprising a one piece metal member having a base portion, eyelets adjacent opposite ends of the base portion for fastening the same to the envelop said base portion being bent intermediate 35 the eyelets to form a projection extending to one side of the base portion, and a bill portion positioned on the same side as the projection and provided with a bendable 40 finger adapted to be moved with the bill portion toward the base portion and to one side of the projection, the side of the projection facing the bendable finger being slit and bent to form a finger bending means 45 adapted to engage the finger when pressed into engagement therewith to bend the finger into locking position.

6. An article of manufacture comprising 50 a stamped metal clasp comprising a flat base portion provided with a bent portion projecting from one side of the flat base portion, one side of said projection having a pair of slits therein and the portion to the sides of the slits being depressed out of the 55 plane of the portion between the slits, the

portion between the slits constituting a finger bending part offset from said flat base portion, and a bill portion provided with a bendable finger adapted to engage said part to be bent thereby.

7. An article of manufacture comprising 60 a stamped metal clasp comprising a base portion provided with a bent portion projecting from one side of the base portion, one side of said projection having a pair of slits therein and the portion to the sides of the slits being depressed out of the plane of the portion between the slits, the portion between the slits constituting a finger bending part offset from said base portion, and a bill 65 portion terminating in a bendable finger adapted to engage said part to be bent thereby, said slits providing an opening adapted to receive the bent finger.

8. A clasp including two members, and 70 means for locking said two members together comprising a portion on one of the members formed between two parallel slits and joined to said member at its upper and lower ends and inclined in one direction, 75 and a portion on the other member bendable in the direction of the incline and adapted to be engaged by the inclined portion and bent when the two members are forced together.

9. A one-piece clasp comprising two members fastened together at one end, means for fastening one of said members in position, a portion of one of said members being adapted to be passed through an element to be positioned between said members, an incline 90 formed on the other member between parallel slits, the portion having the incline being joined to its member at both ends, said portion being bendable in the direction of 95 the incline when engaged thereby.

10. A clasp provided with a base portion, a part of said base portion being bent to form an offset projection, said projection having a pair of parallel slits and being otherwise imperforate with the portion between the slits depressed to form an incline, and a bill portion provided with a bendable finger bendable in the direction of the slits adapted to engage said incline to be guided thereby and 100 bent into locking position.

Signed at New York city in the county of New York and State of New York this 18" day of September A. D. 1917.

GEORGE C. MOXON.
